Primary Examiner — Jae Liang*Assistant Examiner* — Ji Sun Yoon(74) *Attorney, Agent, or Firm* — Crowell & Moring LLP(57) **CLAIM**

The ornamental design for a knife block, as shown and described.

DESCRIPTION

FIG. 1 is a perspective view of a knife block showing the new design;
 FIG. 2 is a front view thereof;

FIG. 3 is a right side view thereof;

FIG. 4 is a rear view thereof;

FIG. 5 is a left side view thereof;

FIG. 6 is a top view thereof;

FIG. 7 is a bottom view thereof; and,

FIG. 8 is another perspective view thereof.

The broken lines are for environmental purposes only and do not form any part of the claimed design.

1 Claim, 5 Drawing Sheets(56)
